SWING SEAT OR THE LIKE

Donald D. Hock, Herrin, Ill., assignor to Mattel, Inc., Hawthorne, Calif.

Filed Jan. 7, 1971, Ser. No. 104,826

Term of patent 14 years

Int. Cl. D21—03

U.S. Cl. D34—5

FIG. 1

FIG. 3

FIG. 2

FIG. 1 is a perspective view of a swing seat or the like embodying my design;
 FIG. 2 is a left side view of same;
 FIG. 3 is a top view thereof;
 FIG. 4 is a right side view thereof;
 FIG. 5 is a bottom view of same;
 FIG. 6 is a front view thereof; and
 FIG. 7 is a rear view.

I claim:
 The ornamental design for a swing seat or the like, as shown and described.
